W. H. FENNEMAN

WELL DRILL PITMAN BEARING

Filed April 16, 1927

Patented July 31, 1928.

1,679,077

UNITED STATES PATENT OFFICE.

WILLIAM H. FENNEMAN, OF TAFT, CALIFORNIA, ASSIGNOR TO MARY KATHERINE FENNEMAN.

WELL-DRILL PITMAN BEARING.

Application filed April 16, 1927. Serial No. 184,371.

This invention relates to new and useful improvements in well drilling machinery, and particularly to the pitmen thereof.

One object of the invention is to improve the construction of the wrist-pin bearing of the pitman, which enables the operator to more easily and quickly remove the pitman from the wrist-pin.

Another object is to provide means for securely holding the upper bearing in engagement with the wrist-pin, and wherein the manipulating means for such holding means is so formed that danger of pinching the fingers is obviated, and danger of the jerk line catching on such means is prevented.

A further object is to provide means for raising and lowering the upper bearing block whereby to prevent any tendency of such block to bind in its guide.

A still further object is to provide a support for the bearing blocks which is removable from the pitman frame.

Other objects and advantages will be apparent from the following description when taken in connection with the accompanying drawing.

In the drawing:

Figure 1 is an elevation of the lower portion of a drilling machine pitman, showing the invention applied thereto.

Figure 2 is an enlarged vertical central sectional view on the line 2—2 of Figure 1.

Figure 3 is a horizontal sectional view on the line 3—3 of Figure 1.

Figure 4 is a horizontal sectional view on the line 4—4 of Figure 1.

Referring particularly to the accompanying drawing, 10 represents the metal strap which forms the side portions of the pitman, and which strap is formed with a curved bight portion 11. Received within this bight portion 11 is a metal casting 12, and formed in the upper central portion of the casting is an upwardly opening angular recess 13, in the side walls of which are formed the longitudinally extending grooves 14. Formed transversely in the casting 12, directly below the recess 13, is a handle loop 15, which the operator is adapted to grasp to lift the casting from the bight of the strap, when necessary. The casting 12 is suitably ribbed, as shown in the drawing, whereby to produce strength therein. Disposed in the lower portion of the recess is

the lower bearing block 16, said block having a wrist-pin receiving recess 17 in its upper face, and vertical ribs 18, in its sides, these ribs being properly fitted within the before-mentioned grooves 14. Disposed through the sides of the bight portion of the strap 10, the casting 12, and the lower bearing block 16, is a bolt 19, one end of which is formed with a shoulder 20, and an eye 21 outwardly thereof. Straddling this eye 65 21 is the bifurcated end of a hand lever 22, a pivot pin 23 being disposed through the lever and eye. Pivottally connected with the lever 22, outwardly of the pivot of said lever, is an upwardly extending link 24, said link having adjustable connections 25, with the lower end of a second link 26. In the upper portion of the recess 13 there is disposed the upper bearing block 27, said block having a recess 28, in its lower face, 70 similar to the recess 17, for embracing engagement with the upper portion of the wrist pin 29, and having the longitudinal ribs 30 engaged in the grooves 14, of the casting 12. Secured to the inner face of 75 one side of the strap 10 is a bracket 31, and pivotally connected to said bracket is one end of a manipulating bar 32, said bar having its other end extended through a slot 33, formed in the other side portion of 80 the strap where it is formed with an eye 34 pivotally connected with the upper end of the before-mentioned link 26. Also connected to this end of the bar 32 is the lower end of a coil spring 35, which has its upper 85 end secured to the side of the strap 10, said spring normally urging the bar 32 upwardly, as will readily be understood. The bar 32 is reduced in thickness downwardly toward its lower edge, and such lower edge 90 is longitudinally curved or bowed, as shown at 36. Formed on opposite sides of this lower edge portion of the bar 32 are the longitudinally extending ribs 37. Formed on the upper end of the upper bearing block 95 27 are the upwardly extending, and properly spaced, L-shaped lugs 38, which are arranged to straddle the lower portion of the bar 32, and rest on said ribs 37. The lower faces of the transverse portion of 100 these L-shaped lugs are curved whereby to permit a rocking movement on the said ribs. Thus when the bar 32 is rocked upwardly or downwardly on its pivot the block 27 105 will be moved vertically in the recess with- 110

out any binding action therewith. The recesses of the bearing blocks 16 and 27 are properly lined with Babbitt metal, for contact with the wrist-pin. The upper block 5 27 is hollow, and has an opening 39 in one side of its upper end to provide for the introduction of lubricant.

It will be particularly noted that the pivotal connection between the link 24 and the lever 22 is such that when the lever is swung downwardly into a position against the side of the bight portion of the strap 10, the said pivotal connection will lie inwardly of the pivotal connection between the lever and the bolt 19, whereby said lever is properly held against accidental outward movement. This position of the lever places the spring 10 under tension, and when the lever is swung outwardly away from the pitman, the spring 15 will pull upwardly on the bar 32, whereby to elevate the upper block 27 to a sufficient distance to free the same from the wrist-pin. The operator then grasps the handle 15, and lifts the pitman from the wristpin. Upon 20 restoring the pitman to a position where the wrist-pin is properly seated in the recess of the lower block 16, the operator grasps the lever 22 and swings the same downwardly,

with the result that the upper block 27 is forced downwardly into engagement with 30 the wrist-pin, said block being thus held by virtue of the off-center connections between the lever and the link 24.

What is claimed is:

A pitman including a yoke, a block seated 35 in the bight of the yoke and having an angular recess, a lower bearing block seated in the recess, a bolt disposed transversely through the yoke, the block and the bearing block, an upper bearing block disposed in the recess and having upwardly extending opposing L-shaped lugs on its upper end, the inner faces of the transverse portions of said lugs being inclined transversely of the lugs, a lever disposed through the arms of 40 the yoke and having longitudinally extending tapered ribs engaged beneath the inclined portions of said L-shaped lugs, and means mounted on said bolts and operatively connected with the said lever for moving the 45 latter to engage and disengage the movable bearing block with respect to a crank pin.

In testimony whereof, I have affixed my signature.

WILLIAM H. FENNEMAN.
